HENRY H. MORETON, OF SANTA MONICA, CALIFORNIA, ASSIGNOR OF ONE-THIRD TO
O. B. ENGLISCH, OF CHICAGO, ILLINOIS, AND ONE-THIRD TO CHARLES F. CRAIG, OF
LOS ANGELES, CALIFORNIA

APPARATUS FOR DISTILLING OILS

Application filed October 8, 1928. Serial No. 311,248.

This invention is an apparatus for treating oils to remove impurities suspended therein.

One of the objects of the invention is to provide a simple and practical apparatus, by means of which such contaminated oils as used crank case oils, cylinder oils, and the like, as well as new oils which contain suspended impurities may be treated so as to effectually remove the suspended matter. A further object is to provide simple means for so treating the oil that impurities carried thereby, and which normally cannot be separated from the oil except by complete distillation, will be effectually acted upon and precipitated, so that they may be readily removed from the oil by any well known method of separation, such for instance as filtration. A further object is to provide simple means for removing gasoline, aqueous moisture, or other similar volatile constituents which may have been taken up by the oil while in use, or during previous treatments, such as the so-called "acid treatment".

25 The invention will be hereinafter fully set forth and particularly pointed out in the claims.

In the accompanying drawings:—

Figure 1 is a side elevation diagrammatically illustrating an apparatus constructed in accordance with the invention, parts being shown in section. Figure 2 is an enlarged view illustrating the volatilizer. Figure 3 is a sectional view illustrating the mixer.

Referring to the drawings, 10 designates a storage tank, and 11 a gravity supply tank. The said tank 10 may be located at any convenient position, and as shown is mounted upon a suitable supporting frame-work 12. The outlet from the tank 10 consists of a pipe 13 and the inlet for the tank 11 consists of a pipe 14 which delivers into the top of the last mentioned tank. Said pipes 13 and 14 are connected by a suitable impelling device, such as an electrically driven pump conventionally illustrated at 15.

The still unit or vaporizer V consists of a plurality of spaced apart vertically disposed chambers 16 of angular cross section and ar-

ranged in a group, and if desired the chambers at one end of the group may be of smaller diameter than those at the other end of the group. The bottom or lower end of each unit 16 is provided with a removable plug 17 to permit access to the interior of the unit. Leading from the top of each unit is a pipe or vent flue 18, which is removably secured to the unit in suitable manner as by means of a threaded and collar connection indicated at 19. The outlet of the tank 11 is connected by means of a pipe 20 with the lower portion of the first unit 16 of the group, said pipe being preferably looped around the vent pipes or stacks 18 as indicated at 20^a so that the oil will receive a preliminary heat treatment before it reaches the first unit 16. It will be noted that the units are alternately connected at the upper and lower ends, nipples or other pipe connections indicated at 21 and 22 respectively. The last unit of the group is provided with a discharge pipe 23 leading from the upper portion thereof. In practice, a battery of units is normally enclosed in a suitable casing as shown in Figure 1.

Any desired number of the units 16 may be employed and arranged in any preferred number of groups, the number shown in the drawings having been selected solely for the purpose of illustration and without desire to limit the invention. Said units are heated in any desirable manner, for instance, by means of a gas burner 24 located below the units, and supplied in suitable manner from a source of gas supply indicated at 25.

The vent stacks 18 of the unit 16 may open directly to the atmosphere, but it is preferred to deliver them into a conduit 27, provided with a suction device 28 designed to propel the vapors to any desired storage receptacle, or other position where they may be safely disposed of. The conduit 27 is preferably provided with an oil separator 29 conventionally illustrated, and also with a drain pipe 30 to permit the draining off of any condensation.

The delivery pipe 23 discharged into a funnel or other guiding device indicated at 31 and located directly beneath the drip open-

ing 30. The funnel 31 serves to direct the oil leaving the vaporizer V into a mixer M which may be of any desired construction. For purposes of illustration, said mixer is 5 shown as consisting of a chamber 35, in which is rotatably mounted a longitudinally disposed shaft provided with agitator blades 36, and operated from any suitable source of power, such as a pulley 37. The oil is delivered from the funnel 31 into the mixer 10 through a hopper 38.

The mixer is also provided with a second hopper 39 leading to the interior thereof, for the purpose of introducing the material 15 which is used for clarifying and treating the oil. This material is in powdered form and may be supplied to the hopper 39 in any desired manner, a bucket conveyor 40 being conventionally illustrated for this purpose. 20 It is to be understood, however, that the material may be deposited in the hopper 39 manually, or by any other known means. From the mixer M the oil and the clarifying agent, which have been very intimately intermixed 25 as they pass through the mixer, are drawn from a delivery pipe 41 into an agitator chamber 42, provided with a stirrer or agitator of any desired construction, which is carried by a shaft 43 driven by a shaft 44 30 through intermeshing gears 45 and 46. It is preferred to heat the chamber in suitable manner, a steam jacket 47 being shown for purposes of illustration. The steam supply and discharge pipes are shown at 48 and 49 35 respectively. The agitator chamber is provided with a suitable clean-up plug indicated at 50.

From the agitator the treated oil is carried 40 off through a discharge pipe 51 to a suitable separating apparatus 52, a pump 53 serving to impart positive movement to the oil. The separating device may be of any desired construction but for purposes of illustration a standard type filter press 52 is conventionally indicated.

In operation, the supply of oil to be treated is drawn from the tank 10 and placed in the tank 11, and when the desired quantity has 50 been supplied to the last mentioned tank, the oil is permitted to flow through the pipe 20 by opening the stop cock which normally prevents this flow. It will be noted that heat from the burner 24 will pass upwardly, around and between the units 16 and heat 55 them to a relatively high temperature. In fact the vent pipes 8 become quite hot under the influence of the burner. The oil flowing through pipe 20 and around the loop 20^a receives a preliminary heating by reason of the 60 heat radiated from the vent flues 18, and as it passes through the units 16 it is gradually heated until at the delivery point 31, it runs from approximately 350° to 400° F. By 65 reason of the heat thus developed any gasoline vapors or other volatile hydrocarbon va-

pors, as well as aqueous vapors will be driven off through the vents 18, and carried off by the action of the suction device 28. The oil is separated and any condensation which may occur is delivered to the funnel 31 through 70 the drip opening 30. It is an interesting factor that although the feed from the tank 11 is by gravity, and the flow from unit to unit is through the connections 21 and 22 the units 18 must be extended a substantial height 75 above the upper ends of said units because the flow from one unit to another is not fast enough to prevent a certain amount of back-ing-up of the oil into the vent flues 18.

As the oil is supplied to the mixer M, the conveyor 40 is also put in operation, and by means thereof calcium sulphate is discharged through the hopper 39 into the mixer M. The agitator blades 36 effect a thorough and intimate mixing of the oil and the calcium sulphate as they pass through the mixer, so that by the time they are discharged into the agitator 42, the calcium sulphate has been uniformly distributed throughout the oil. After being deposited into the agitator 42 the 90 mass of oil and calcium sulphate is agitated and heated, so as to enhance and increase the action of the calcium sulphate which has the effect of attracting the mechanically suspended impurities and carrying them down as a 95 precipitate. The mass must therefore be continuously agitated to avoid too early separation, and heated to quicken the attraction of the suspended particles for the calcium sulphate and for each other.

The pump 53 serves to transfer the mixed oil and calcium sulphate to the filter press before any substantial separation can take place, and then the impurities, which have 105 taken a form of small masses of sufficient dimensions to be readily visible to the naked eye are quickly and easily separated by the filtering action. The result is the production of a very high grade oil from which all mechanically suspended impurities have been 110 removed. This is true whether the impurities consist of the very fine carbon particles which are normally suspended in used crank case oil, or whether they are gummy substances which are often suspended in oil and not 115 readily detectable, or whether they include the burned particles of oil resulting from attempts to bleach by the use of sulphuric acid. The fine particles cannot ordinarily be removed except by complete distillation, are effectually removed by the apparatus described. The oil treated by the apparatus above described is not only highly purified, but its lubricating properties are in no way 120 impaired. In fact, experience has proved 125 that its viscosity and lubricating properties are greatly enhanced by the treatment.

The calcium sulphate is preferably in the form of plaster of Paris or gypsum, but the invention is not limited in this particular be- 130

cause other calcareous cements may be employed in lieu thereof, such as natural cement, Portland cement, and the like. Therefore, wherever the term "calcium sulphate" is used in this specification and the appended claims, it is to be understood that the above mentioned substances are to be considered as equivalents and within the spirit of the invention.

10 While it is impossible to definitely state whether the action of the calcium sulphate is a chemical one or a physical one, or both, the fact is that when this substance is brought into contact with oil, it appears to attract 15 the mechanically suspended impurities carried by the oil and to precipitate them instantly. And during the precipitation, finer particles, which ordinarily would not be visible to the naked eye appear to be attracted 20 to each other, so that they form minute masses which are coarse enough, however, to be readily separated by filtration. It has also been found that calcium sulphate will also bleach oil which has been subjected to what 25 is known as the acid treatment.

The advantages of the invention will be readily apparent to those skilled in the art of purifying oils. It will be particularly noted that a very simple and inexpensive apparatus is provided, by means of which the volatile constituents are readily removed without subjecting the oil to what is usually understood as the distillation process. A further advantage is that the mechanical impurities are treated in a convenient and effective way to permit of their ready and complete removal from the oil. It will be noted that the vaporizer is not only effective in the treatment of the oil, as an adjunct of the complete apparatus disclosed herein, but it may be also used for separation of hydrocarbon vapors of different specific gravities.

Having thus explained the nature of the invention and described an operative manner of constructing and using the same, although without attempting to set forth all of the forms in which it may be made, or all of the forms of its use, what is claimed is:—

1. In an oil purifying apparatus, a vaporizing unit comprising a plurality of vertically disposed vaporizing chambers, each provided with a vertically disposed vent flue leading from the top thereof, said flues being of less diameter than the chambers, pipes connecting the consecutive chambers alternately at the top and bottom, means for heating said chambers, a collecting flue into which the vent flues discharge, and a suction device for removing vapors from said collecting flue.

2. In an oil purifying apparatus, a vaporizing unit comprising a plurality of vertically disposed vaporizing chambers, each provided with a vertically disposed vent flue leading from the top thereof, said flues be-

ing of less diameter than the chambers, pipes connecting the consecutive chambers alternately at the top and bottom, means for heating said chambers, a collecting flue into which the vent flues discharge, an oil separator in 70 said collecting flue, a suction device for removing vapors which pass said separator, and means for carrying off condensates which are removed from the vapors by said separator.

3. In an oil purifying apparatus, a vaporizing unit consisting of a plurality of vertically disposed vaporizing chambers, each provided with a vertically disposed vent flue leading from the top thereof, said flues being of less diameters than the chambers, pipes connecting the consecutive chambers alternately at the top and bottom, said flues being extended a substantial height above the vaporizing chambers so as to prevent backing 80 up of the oil into the vent flues, means for heating said chamber, an oil feed pipe connected with one of said chambers, said pipes having a loop extended around the flues so that the oil may be preheated, and a collection 85 flue into which the vent flues discharge.

In testimony whereof I have hereunto set my hand.

HENRY H. MORETON.
